UNITED STATES PATENT OFFICE.

JACOB STOCKE, JR., OF ST. LOUIS, MISSOURI, ASSIGNOR TO PROGRESS PRESS BRICK & MACHINE COMPANY, OF ST. LOUIS, MISSOURI, A CORPORATION OF MISSOURI.

DESIGN FOR A BUILDING-BRICK.

51,767.

Specification for Design.

Patented Feb. 12, 1918.

Application filed October 18, 1917. Serial No. 197,349. Term of patent 14 years.

To all whom it may concern:

Be it known that I, JACOB STOCKE, Jr., a citizen of the United States, residing in the city of St. Louis and State of Missouri, have invented a new, original, and ornamental Design for a Building-Brick, of which the following is a specification, reference being had to the accompanying drawings, forming part thereof.

In the drawings,

Figure 1 is a perspective view of a building brick, showing my new design, and

Fig. 2 is an enlarged perspective view of one corner of a brick, illustrating my design.

Referring to the drawings, Fig. 1, the top, bottom and rear faces of the brick are smooth plain faces; my new and ornamental design being produced on the front face and both ends. The new and ornamental design

on each end being the same, and is the same design as appears on the front face of the brick. Each end of the brick at each corner is provided with a plain face of substantially equal width which are slightly inclined inwardly. Between these two plain faces on each end, (the design on each end being alike) my new and ornamental design comprises a series of projections, which projections are produced by intersecting or cutting on parallel lines at equal distances apart a series of parallel V-shaped ridges.

I claim:

The ornamental design for a building brick as shown and described.

JACOB STOCKE, JR.

Witnesses:

JACOB STOCKE, Sr.,
E. L. WALLACE.
